UNITED STATES PATENT OFFICE.

ALBERT H. ANTZ, OF SAN FRANCISCO, CALIFORNIA, ASSIGNOR TO SIERRA ART & ENGRAVING CO., OF SAN FRANCISCO, CALIFORNIA, A CORPORATION OF CALIFORNIA.

COOLING MACHINE.

Application filed November 13, 1924. Serial No. 749,719.

To all whom it may concern:

Be it known that I, ALBERT H. ANTZ, a citizen of the United States, and a resident of San Francisco, county of San Francisco, State of California, have invented a new and useful Cooling Machine, of which the following is a specification.

My invention relates to cooling machines for use in the process of engraving.

10 In what is called the burning-in step of an etching process, it is common and well known in the art to subject the plate to be etched successively to the action of heat in time with the process of brushing the plate with an acid resistant, commonly called "dragon's blood," and to successively cool the plate in time with the aforesaid heating steps. This cooling is generally effected by passing the hot plate over a water-saturated roller to chill same ready for the next heating and brushing thereof. The plate is then passed over an absorbent surface to take up the waste or excess moisture or drippings left by the cooling bath.

15 In this well-known method of handling the plate, great care must be exercised that the top or partially etched side of the plate is not splashed with the cooling water, because, if the etched side is touched by the water, even a small drop will spot the plate and necessitate costly and laborious treatment to restore the plate to its intended form. Cooling rolls over which the bottom side of the plate is passed are horizontally 20 mounted on a table or stand and as the plates are frequently large and heavy and passed over the rolls at a tangent thereto, the plate is liable to buckle. Particularly 25 in the production of color plates this distorts the plate and sometimes renders same valueless.

It is an object of my invention to provide a cooling machine which satisfactorily overcomes the objections heretofore existing in the art, and to provide means to eliminate buckling of the plate and unequal contraction due to unequal cooling and for avoiding the use of water in the cooling step or treatment, whereby the plate is dry at all 30 times.

A further object of the invention is to provide a cooling machine where the air is employed as a cooling agent for the plate, and my invention makes use of a structure

and coacting instrumentalities whereby the full force and effect of the air is spent against both sides of the plate, augmenting the cooling process and enabling same to be carried on with dispatch and in a manner that will enable an operator to heat and brush one plate while another is being treated to a cooling action.

Other features of novelty and utility will obviously appear upon reference to the accompanying drawings and description, wherein:

Figure 1 is a plan view of my improved cooler with parts broken away for the purpose of clearness, and

Figure 2 is a side elevation thereof. 70
In carrying my invention into practice, use is made of an upper truncated cone or pyramid-like section 5, and a lower truncated cone or pyramid-like section 6, the latter arranged directly under or in vertical alinement with the former so that the respective small ends of both sections are on a common line drawn vertically through the complete structure. The large ends of the sections 5 and 6 are brought almost together and are joined to one another by a skirt or angular wall 7, and in one part of which is a swinging door 8. The door may be turned on its mounting by means of a manually actuated crank handle 9. When tilted in one direction, access may be had to the double truncated receptacle or chamber defined by the two sections 5 and 6. When closed, the door serves to cover what I shall call the open side of the chamber. 90

Behind the door 8 and supported in the structure at its point of maximum diameter are spaced apart bars or supports 8^a, on which the metal plate to be treated is adapted to rest in a horizontal position. 95 These bars hold the plate flatwise. They equally sustain the weight of the plate so that it is impossible for the plate to buckle.

The two sections 5 and 6 are supported upon a vertical frame 10 having a base platform 11. A motor driven blower is conventionally illustrated at 12, and the duct 13 thereof makes connection with the small end of the section 6 so that a blast of air will be impelled into the section 6 below the bars 8^a where it will be brought into direct impingement with the bottom side of the metal plate. 105

A metal plate under course of treatment is shown at A, and as the combined horizontal area of same is less than the combined horizontal area of the space bounded by the 5 walls of the aforesaid skirt 7, it follows that passage-ways are formed between the edges of the plate and the inner surfaces of said skirt. It consequently happens that an air lane created in the entire structure is 10 intercepted by the supported metal plate in its course of treatment, and that the full force and cooling effect of the air is first applied and made to impinge against the bottom side of the metal plate.

15 The air, in seeking its escape from the lower section 6 of the structure, is forced upwardly past the edges of the plate and is finally buffeted by the angular walls of the upper section 5. At this time, the air is still 20 at a relatively low temperature and same possesses good cooling qualities. The final discharge of the air is effected by the outlet at the top of section 5, but the outlet being constricted as compared with the internal 25 area of said section 5, causes deflection of the air over the top of the metal plate and same is accordingly utilized as an effective cooling agent.

In effect, I create a lane of cool air and 30 intercept same by positioning a hot metal plate between the source of air intake and the source of air discharge. I cause the intercepted air to impinge against both sides of the plate while constantly inducing a 35 cooling draft within the structure.

It is found in practice that the top section 5 on account of its given form acts to 40 squeeze the air as it flows in an upward direction past the edges of the plate A and I thereby cause radial deflection of the air across the top of the plate. This results in a final cooling of the plate with great rapidity and thoroughness. In fact, it follows from the stated combination of parts herein 45 mentioned and the form and construction of the parts, that the time consumed in cooling a plate is practically in coincidence with the time required to prepare another plate for a cooling treatment, and I am therefore 50 able to successively treat a number of plates without loss of time or interruption.

Broadly speaking, my invention centers upon means for horizontally supporting a plate, and means for employing air first 55 against one side of the plate and then against the other side thereof, one side re-

ceiving a fresh blast of air at low temperature and from which said side the air is constricted in its discharge and then finally permitted to pass over the top of the plate, 60 where its discharge is further constricted while the air is still at a low temperature.

I have described specifically a chamber of substantially double truncated form, as I find from practice that very satisfactory 65 results can be obtained therefrom. However, it shall be understood that I do not wish to limit myself in respect to the structural details herein exhibited, and that changes within the scope of the hereto annexed claims can be made within the spirit 70 of my invention.

Neither do I wish to limit myself as to size and kinds of materials employed, but in this respect it shall be remembered that 75 a plate to be treated must be of a size less than the maximum size of the cooling chamber at the point where the plate rests. This is important in order that proper passage of air from the lower section 6 may be had at 80 points around the edges of the plate from which the air finally passes to the section 5 to be constricted and buffeted by the walls of said section and held substantially superposed with respect to the etched side of the 85 plate.

Intercepting an air lane by supporting a plate at some point in the lane and utilizing the air against both sides of the plate is the 90 feature of novelty with which I am particularly interested whereby the cooling action can be carried on with thoroughness and rapidity.

I claim:

1. In a cooling machine of the class described, a double truncated cooling chamber, open at one side between its small ends, a closure for said open side, and means for supporting a plate in said chamber between said small ends so that air impelled through the chamber will be intercepted by the plate. 95
2. In a cooling machine, a chamber whose internal diameter respectively reduces in two directions from its center, means for supporting a plate in said chamber at the large part thereof, and means for causing an induced air current to flow through said chamber and to be brought into impingement first against one side of the supported plate and then against the other side 105 thereof. 110

ALBERT H. ANTZ.
